Primary Examiner — Susan Bennett Hattan*Assistant Examiner* — Rebecca Tsehay(74) *Attorney, Agent, or Firm* — Trego, Hines & Ladenheim, PLLC; Brandon Trego; Jonathan Hines(57) **CLAIM**

I claim the ornamental design for a corner protector, as shown and described.

DESCRIPTION

FIG. 1 is a perspective view of a corner protector, showing my design;

FIG. 2 is a top view of the corner protector of FIG. 1;

FIG. 3 is a bottom view of the corner protector of FIG. 1;

FIG. 4 is a front elevation of the corner protector of FIG. 1;

FIG. 5 is a rear elevation of the corner protector of FIG. 1;

and,

FIG. 7 is a right elevation of the corner protector of FIG. 1.
